UNITED STATES PATENT OFFICE.

EARL A. THISSELL, OF LOWELL, MASSACHUSETTS, ASSIGNOR TO THE DENNIS CASH CARRIER COMPANY, OF SAME PLACE.

CASH-CARRIER.

SPECIFICATION forming part of Letters Patent No. 286,504, dated October 9, 1883.

Application filed September 5, 1883. (No model.)

To all whom it may concern:

Be it known that I, EARL A. THISSELL, of Lowell, in the State of Massachusetts, have invented certain new and useful Improvements in Cash-Carriers, of which the following is a specification.

My invention has relation to the cash-carrier proper, and is directed to the means by which the coin or other article placed therein is centered and held securely.

The carrier in which my invention is embodied is a two-part carrier, one of whose parts may be termed the "body," and the other the "cover." The instrumentality I employ for holding and centering the article placed inside the carrier is a hollow rubber ball, which I prefer to provide with a small vent, so as to be more readily collapsible. I prefer to employ one of these balls in each part of the carrier, the two being so placed that they will meet and be pressed together when the two parts of the carrier are put together. It is also preferred to employ in one of the parts of the carrier—for instance, in the body—a disk or dished plate, which rests on or against the ball therein, and serves to hold in place the coin or other article before the two parts are put together. If desired, but one ball can be employed, this ball being placed in one of the parts—as, for instance, in the cover—while the disk or dished plate is secured in the other part.

The accompanying drawings represent the preferred embodiment of my invention.

Figure 1 is a longitudinal central section of the carrier closed and ready for use. Fig. 2 is a like section of the same open, or with its two parts separated from one another.

The carrier is, in this instance, of cylindrical form, and is provided at each end with an annular flange, *a*, one of which is formed on the body *A* and the other on the cover *B*. In the peripheral groove of each flange is held a rubber tire, *b*. These tires, being intended to run in grooved track-rails, are of corresponding form. This feature, however, is not of my invention. The cover *B* is adapted to fit within the body *A*, and when fitted in place is held by a bayonet-joint, *b'*.

Fitting and secured in the cover is a hollow elastic rubber ball, *C*, and within the body *A* is secured, in like manner, a similar ball, *C'*. To make these balls more readily collapsible, each one is provided with a small vent, *c*, which communicates with a hole, *d*, in the head of the cover *B* and body *A*, respectively. The two balls are of such size or are so placed that they will normally meet and be pressed together when the two parts *A* *B* are put together.

In front of the body ball *C'*, I prefer to place the disk or dished plate *D*, hereinbefore referred to, which can move back and forth in the body *A*, and is preferably attached to the ball *C'*, so as to move therewith.

To use the carrier, the cover is removed and the coin or other article is placed on the disk *D*, the body being held open-end uppermost. The cover is then fitted in place, with the effect of causing both balls to be pressed back or collapsed equally, the coin being held tightly and firmly by the elastic pressure of the ball between the disk *D* and ball *C*, as indicated in Fig. 1, where the coin is represented at *E*. As hereinbefore intimated, the disk *D* may be dispensed with, and the coin may be held directly between the two rubber balls. On the other hand one of the balls may be dispensed with—as, for instance, the ball *C'* in the body—in which case the coin would be held between the disk *D* and cover-ball *C*. In such event the disk *D* either could be movable and backed by any suitable spring or elastic support; or it could be fixed in place, since the ball *C* would yield to the requisite extent. I prefer, however, on the whole, the arrangement of parts illustrated in the drawings.

What I claim as new and of my own invention is—

1. The combination, with a two-part carrier, of a collapsible elastic hollow rubber ball in the one part, and an opposed co-operating surface in the other part, between which and the rubber ball the coin or other article placed in the carrier is held when the two parts of the carrier are fitted together, substantially as set forth.

2. The combination, with the two-part car-

rier, of the hollow elastic balls C C', substantially as and for the purposes hereinbefore set forth.

3. The combination, with the two-part carrier, of the hollow elastic balls C C', and interposed disk or plate D, substantially as and for the purposes hereinbefore set forth.

4. The combination, with the two-part carrier, of the hollow elastic balls C C', provided

with vents communicating with holes in the heads of the carrier, substantially as and for the purposes hereinbefore set forth.

In witness whereof I have hereunto set my hand this 25th day of August, 1883.

EARL A. THISSELL.
